UNITED STATES PATENT OFFICE.

EDWIN G. COBELLi, OF MIAMI, FLORIDA.

SALT SHAKER.

Application filed June 18, 1928. Serial No. 286,296.

The present invention relates to an improved shaker for salt, pepper or other condiments, or in fact for powdered or finely divided material which it may be desired to take out of the box or other receptacle; and the invention consists in certain novel features of construction which will be herein-after described and claimed.

In the drawing:

10 Figure 1 is a side elevation of the shaker embodying the features of my invention, and

Figure 2 is a vertical section therethrough.

Referring to the drawing in detail it will be seen that the box or body 5 is in the preferred embodiment of a frusto-conical formation merging at its upper smaller end into a cylindrical externally threaded neck 6 to receive the internally threaded flange 7 20 of the concavo-convex cap 8.

The lower or larger end of the frusto-conical body 5 merges into an inverted frusto-conical flange 9 the bottom of which merges into a ring bottom plate 10. The inner edge of the ring bottom plate 10 merges into a substantially frusto-conical discharge funnel directed up into the body 5.

This funnel is curved longitudinally with its convex surface inwardly. This funnel merges into a concavo-convex perforated top 12.

By moving the shaker up and down in substantial vertical direction it will be seen that the contents thereof will be directed upwardly and suspended in the upper por-

tion of the structure so as to gravitate down through the apertured cap 12.

The shaker may be made of metal, glass or other suitable material. The present embodiment of the invention has been disclosed in considerable detail merely for the purposes of exemplification since in actual practice it will attain the features of advantage enumerated as desirable in the statement of the invention and the above description. 45

It will be apparent that changes in the details of construction, and in the combination and arrangement of parts may be resorted to without departing from the spirit or scope of the invention as hereinafter claimed or sacrificing any of its advantages. 50

Having thus described my invention, what I claim as new is:

A shaker of the class described comprising a frusto-conical body merging at its upper end into a cylindrical neck, a cylindrical flange detachably engaged on the neck and having a concavo-convex cap thereon, the bottom edge of the body merging into a downwardly directed inverted frusto-conical 55 flange merging in turn to a horizontally inwardly directed ring plate bottom which merges in turn into an upwardly and inwardly directed frusto-conical funnel terminating into a concavo-convex perforated extremity, the funnel being longitudinally 60 curved to present an inwardly disposed concave face. 65

In testimony whereof I affix my signature.

EDWIN G. COBELLi.
